DESIGN FOR PRINTERS' TYPE.

The Schedule referred to in these Letters Patent and making part of the same.

To all whom it may concern:

Be it known that I, GEORGE WILLIAM WITHAM, (as-signor to MACKELLAR, SMITHS & JORDAN,) of the city and county of Philadelphia, Pennsylvania, have invented and produced a new and original Design for a Printing-Type; and that the following is a full, clear, and correct description of the same, reference being had to the accompanying drawings, in which the entire alphabet is shown, made in accordance with my design, which design may be preserved in any numerals, signs, or symbols to be used in connection with the alphabet, or any portion of it.

In some cases the design is used with an open letter; in other cases with a closed letter, as seen in the word "Bank."

What I claim as new, and desire to secure by Letters Patent, is—

The within-described design for a printing-type, as shown.

GEO. WM. WITHAM.
